MECHANICAL PENCIL OF THE
PUSH-BUTTON TYPEObed M. Russell, Des Plaines, Ill., assignor to
Raymond T. Moloney, Chicago, Ill.

Application March 31, 1948, Serial No. 18,171

2 Claims. (Cl. 120—17)

1

This invention pertains to writing implements, particularly mechanical or push-button operated pencils and lead feeding or propelling means therefore.

The principal object of the invention is the provision of a simplified and easily manufactured and assembled mechanical feed consisting of a clutch collet and novel sleeve actuator operated by a push-button element in the cap of the pencil.

Additional objects relate to the provision of a clutch and feed assembly consisting of an insert, a clutch tube slidable in the insert, a reciprocable feed tube operated by the push-button, and a tapered actuator sleeve operatively interconnecting the two tubes for joint advance (to propel the lead) in certain conditions, and to free a clutch collet for restorative movement after the writing lead has been advanced, together with certain assembly features and structural novelties thereafter appearing.

Other objects and aspects of novelty in the pencil relate to details of the construction and operation of the embodiment disclosed hereinafter in view of the annexed drawing in which:

Fig. 1 is a vertical section through the novel pencil structure;

Fig. 2 is a horizontal section along lines 2—2 of Fig. 1;

Fig. 3 is a horizontal section along lines 3—3 of Fig. 1;

Fig. 4 is a fragmentary vertical section, similar to Fig. 1, but showing the parts in advanced feeding position;

Fig. 5 is a magnified sectional detail of the clutch collet and operating sleeve in normal position;

Fig. 6 is a perspective detail (with parts shown in section) of the clutch collet and operating sleeve.

Referring to Fig. 1 the pencil consists of the usual tubular body or barrel 10, with pocket clip 11, and clip-retaining bushing 12 threaded into the barrel as at 13.

At the lower end of the barrel is the conventional tapered tip 14 threadably engaging at 15 the lower end of a machined insert 16 shouldered at 17 to engage a seating shoulder in the barrel. Within the lower portion of the tip is a friction sleeve 18 through which the writing lead 19 emerges and which serves to prevent short or broken pieces of lead from falling out.

Interiorly of the barrel is a magazine sleeve 20 having crimped into its upper portion a lead baffle 21 with a central concavity and lead opening

2

22 through which the leads are introduced to the magazine space 23. At the upper end of the magazine is a push-button cap or closure 24 frictionally fitting into the magazine sleeve, and having frictionally fitted therein the usual eraser insert 25.

At about the middle of the magazine sleeve a feeding plug 26 is secured by crimping as at 27 with conical infeed opening 28 through which the pencil leads gravitate into the feeding mechanism.

Threaded into said plug as at 29 is a feed tube 30, terminating at its lower end in a head 31. The lower end 29A of the magazine sleeve fits slidably over the machined insert 16, threaded into the upper end of which is another plug 32. Expanded between the feed plug 26 and the plug 32 is a compression spring 33 which normally elevates the magazine sleeve assembly and its push-button cap 24, as well as the feed tube 30 to normalize the same, the latter tube being freely slidable in plug 32.

Crimped onto the enlarged head 31 of the feeding tube is a clutch or collet operating sleeve 35, which moves with said tube and the magazine sleeve responsive to operation of the push-button 24. This construction is shown to advantage in Figs. 5 and 6, also.

The interior of operating sleeve 35 is tapered, being wider at its upper end, adjacent head 31 and narrower at its lower end, for reasons to appear.

The lead-feeding clutch means includes a clutch tube 36 (Fig. 6 also) having an enlarged upper end or split collet head 37 situated within the tapered operating sleeve 35, and at the lower end of the clutch tube is an enlargement or head 38 wedged thereon and retaining the clutch tube assembly within the base of the machined insert, and limiting the upward movement of this assembly by normalizing or retracting spring 33.

Operation

When the parts are in the normal position shown in Figs. 1 and 5, spring 33 elevates magazine tube 20, and hence the feed tube 30, and hence the clutch operating sleeve 35, so that the narrower tapered portion thereof grips the tapered exterior of the collet head 37 and squeezes the latter closed on the pencil lead, to grip the latter.

When push-button 24 is depressed, the parts move downward toward the condition of Fig. 4, and at first the clutch tube 36 is carried downwardly by the frictional grip of the operating

sleeve 35 on collet head 37, which grips the pencil lead and, accordingly, forces the latter downwardly to project from the tip for writing.

When the lower enlargement or clutch stopping head 38 reaches the bore shoulder 39, as in Fig. 4, the descent or advance of the clutch tube is arrested, but the operating sleeve 35 can continue its downward travel somewhat, with the result that the narrower (lower) portions of the internal taper in sleeve 35 disengage the collet head, releasing the grip thereof on the pencil lead, by reason of which release, the operating sleeve, when normalized or returned upwardly by spring 33, does not again grip the collet head until it reaches the upward limit of its return travel, so that the advanced lead will not be retracted.

From the foregoing disclosures, it will appear that the clutch feed consists of an assembly comprising, broadly, the machined insert 16, the clutch tube 36 slideable therein, the actuator or coupling sleeve 35 also slideable in the insert, the magazine sleeve 20 slideable on the insert (and guided also by the barrel) the reciprocable feed tube 30 fixed to the actuator sleeve, and the included normalizing or return spring 33.

The insert assembly is secured in the barrel by the threaded tip 14.

The actuator sleeve 35 normally grips and closes the clutch and advances the same during part of the advancing or feeding movement, then slidably disengages the clutch head or collet during the remainder or overtravel of said advancing movement.

Upon return of the actuator or clutch sleeve 35, the collet head 37 is not again closed upon the advanced lead until the sleeve is substantially in normally elevated position. The headed end 31 of the feed tube does not at any time grab the lead, so that the new leads descending from the magazine will pass freely into the clutch collet or head when the latter is opened.

The assembly may be removed easily from the barrel.

The word "insert," as used herein, designates the machined, stepped, member 16, and is defined to mean a member of tubular configuration adapted to fit into assembled relation with other tubular parts, substantially as disclosed.

The term "normalized," as used herein, is defined to mean returned to normal, as in the condition of collet tube 30, and its associated members 26, 20, disposed in the normal condition, seen in Fig. 1, by action of spring 33.

Having thus particularly described the construction and operation of the novel pencil mechanism, the invention claimed is:

1. In a mechanical pencil, a barrel having a tapered lower end and an open upper end, a bored insert fitted into the lower end of the barrel, a feeding tube and a collet tube aligned in the bore of the insert, the latter having a collet confronting the proximate end of the feeding tube, a collet-actuating sleeve fixed on said proximate end to surround said collet and having an internal taper widened at one end to disengage said collet and permit opening of the same and narrowed at an opposite end to seize and close the collet, said tube ends, collet and sleeve being situated within said insert, the upper end of said insert being spaced from the internal walls of said barrel, a magazine tube having an upper end structure exposed for operation as a plunger at the open end of said barrel and a mid-portion coupled with said feed tube to reciprocate the latter and the sleeve responsive to plunger action

of said magazine tube, the latter having a lower skirt slidably guided on said spaced portions of the insert, a tip portion at the tapered end of said barrel and threadedly engaged with said insert, lead-gripping friction means in said tip to grip the lead against retraction, said collet tube having an opposite end provided with a stop portion engageable with the lower end of said insert to limit upward movement of the collet tube, said tip affording a stop for said stop portion on downward movement of the collet tube, the tip, barrel, and insert being mutually held in assembly as aforesaid by engagement of the tip with the insert and engagement of the insert with the tapered portion of the barrel, said sleeve having overtravel when the collet tube is stopped downwardly to disengage and release the collet, and to seize and close the collet and elevate the collet tube upon upward movement, and spring means in the barrel normally urging the magazine tube to an upward limit determined by said stop formation on the collet tube aforesaid.

2. In a pencil, clutch and feed means including, a pair of lead feeding tubes reciprocable in axial alignment between opposite limited positions, a coupling sleeve surrounding adjacent ends of said tubes and secured to one tube, a lead clutch adapted to be seized and closed by said sleeve when said one tube is in a normal limited position and coupling said tubes for joint movement away from said normal position to advance the lead, stop means for arresting travel of the second tube after a predetermined amount of said joint movement, said coupling sleeve being of a length to permit overtravel of the one tube after arrest of the second tube, said clutch being released from seizure by the coupling sleeve during said overtravel, said coupling sleeve having a tapered portion coaxing with said clutch during return travel of the one tube toward said normal position to restore said second tube to normal position without closing said clutch until both tubes are restored to normal position, a third tubular element freely surrounding said adjacent ends of the pair of tubes and said sleeve and clutch parts, a barrel in which said third tubular element is fixed, a magazine cylinder reciprocable in said barrel, and having a lower end telescoping upon said third tubular element, a lead infeed plug fast with said cylinder at its upper end, a bored plug confining said sleeve and clutch parts in said third tubular element, a compression spring in said cylinder and having one end seated against said bored plug and an opposite end against said lead infeed plug fast with said cylinder to move the latter away from said third tubular element to a said normal position, said first feeding tube being secured with said infeed plug to move said first tube and said clutch correspondingly to said normal position.

OBED M. RUSSELL.
